UNITED STATES PATENT OFFICE.

LOUIS PHILIPP COHEN, OF NEW YORK, N. Y., ASSIGNOR TO GERTRUDE LEVE, OF NEW YORK, N. Y.

FURNACE.

No. 913,697.

Specification of Letters Patent.

Patented March 2, 1909.

Application filed November 15, 1904. Serial No. 232,794.

To all whom it may concern:

Be it known that I, LOUIS PHILIPP COHEN, a citizen of the United States, and a resident of the city of New York, county and State of New York, have invented certain new and useful Improvements in Furnaces, of which the following is a specification.

This invention relates to furnaces, and has particular application to certain improvements in the construction and formation of the top wall or roof thereof.

It has been found by experience that in large furnaces, such as those equipped with mechanical stokers, better results are obtained in the free combustion of the fuel if the top wall at the mouth of the furnace lies in a straight horizontal plane, instead of being curved or arched, as is commonly the practice. This is due to the fact that the combustible gas generated by the distillation of coal, especially the carburetted hydrogen gas, accumulates in large volumes in the recess of the arch and interferes with the proper burning of the fuel. But when an approximately straight line wall, beveled or inclined toward the furnace on its under side, is substituted for the arch, the gases striking against the wall are directed downward close to the body of the fire and mixing with air introduced through an air pipe or duct adjacent to such wall are consumed, and assist in the free combustion of the fuel products. This straight line top wall has heretofore been constructed of blocks of stone, fire-brick, or the like, cemented together by mortar or similar material. A wall of such formation embodies certain disadvantages, inasmuch as it is difficult and expensive to repair. For instance, should a certain block or brick in the wall be burned out, or otherwise rendered useless, the furnace must be thrown out of operation for a considerable period of time, while almost the entire wall is rebuilt as it is practically impossible to remove a single stone or brick without disturbing and disengaging those adjacent. It is, therefore, my intention to overcome such disadvantages by constructing the wall and providing certain mechanism whereby an individual brick or a series of the same may be easily and readily removed and others substituted, with a minimum expenditure of time and labor and without disturbing the entire top wall.

My invention consists in the construction, 55 combination and arrangement of parts set forth in the appended claims.

In the accompanying drawings wherein I have delineated a preferred embodiment of my invention similar characters of reference 60 designate similar parts in all the groups.

Figure 1 is a vertical sectional view of a portion of a furnace provided with my improvements; Fig. 2 is a view in rear elevation of a wall constructed in accordance with 65 my invention, such view also illustrating the clamping supports employed for retaining the individual blocks in position; such view being taken along the line 2, 2, of Fig. 1, in the direction of the arrows. Fig. 3 70 is a view partly in elevation and partly in section, showing mechanism employed for tightening up the bricks of the wall by forcing such bricks into contact with each other; Fig. 4 is a perspective view of one of the 75 bricks or blocks employed in my furnace, such view also showing the asbestos sheet designed to be interposed between the individual bricks.

Referring to the accompanying drawings 80 in detail, and particularly to Fig. 1, the letter A designates the main front wall of a furnace, such wall being provided with the usual throat B and a curved or arched recess C. Depending from the front of the 85 furnace in such manner as to form a face for the arch is a relatively large plate of sheet metal, such as is shown at 5. A tubular air bar 8 having a web 7, is secured to the plate 5 by the rivets 6. This air bar extends 90 across the entire front of the furnace mouth, and has communicating with its hollow interior 9 a plurality of short ducts 10 through which air is designed to be supplied to the fire on the grate, to assist in the combustion of the gases generated by the distillation of the coal. The tubular air bar 8 is formed of any suitable metal and on the face adjacent to the furnace is provided at its upper end with a shoulder 11, and at its 100 lower edge with the flange 12, the space between the shoulder and the flange forming a groove in which one edge of the fire bricks may be supported, as is hereinafter described. At its outer vertical face the tubular air bar is designed to assist in the support of the stoking hopper, D, as is clearly shown in Fig. 1, but as the present invention

in no wise relates to the construction of this hopper or its manner of operation, it is unnecessary to describe the same in detail here.

My improved fire wall, which is designed to extend across the mouth of the furnace in an approximately straight horizontal line, is composed essentially of a plurality of bricks or blocks E, the construction of which is clearly shown in Figs. 1 and 4. Each block 10 is formed with shoulders 13 and 14 on opposite sides or faces, and on the side having the shoulder 14 the face of the block is beveled or inclined, as is shown at 15, the purpose of this being that when the blocks are assembled to form the wall the gases will strike against such beveled face and be deflected to a position close to the body of the fire. The straight vertical face 15^a of the brick which is shown on the same side as the 20 shoulder 13 is designed to rest in contact with the lower edge e of the arched recess C, so that the assembled blocks will cut off all communication between the recess C and the mouth B of the furnace, thus preventing the 25 heat passing into the recess C and affecting the brick-retaining mechanism, for as such mechanism is formed of metal, it will be evident that it would be injuriously affected if subjected to a high temperature.

When the bricks are to be assembled to 30 form the wall, an asbestos sheet F is placed over each alternate brick, as is shown in Fig. 2, so that each brick will fit snugly or tightly against those adjoining, and a solid 35 wall possessing fire-proof qualities will be provided. In erecting the wall each brick is placed with its shoulder 14 resting upon the flange 12 of the tubular air bar, the face of the brick directly above said shoulder 14 fitting snugly in the groove formed as heretofore described, by the shoulder 11 and the flange 12. In order to support each 40 brick independently so that it may be removed without disturbing its neighbors, I have provided the following mechanism: 45 Riveted, or otherwise secured, to the inner face of the web 7 is a bifurcated lug 16 to which is pivotally secured the support 17. This support, which may be formed of any 50 suitable material, such as metal, is in the form of an angular arm, comprising the horizontally extending portion 18, when in position, and the vertically depending part 19 having a hook 20 formed at its lower free 55 end. As is clearly shown in Fig. 1, this hook is designed to fit into and engage with the recess formed by the shoulder 13, and at its upper end such arm may be adjusted through means of the screw bolt 21 pivoted 60 at 22 to a supporting arm, said bolt extends through the web 7 and carries at its outer end an adjusting nut 23 adapted to move along the bolt and holding the hanger arm or support in a desired position. After the 65 bricks have been assembled in position and

are secured in place through the medium of the hanger arm as described, it may be necessary owing to certain irregularities in either the size of the bricks or the construction of the furnace opening to adjust the 70 bricks relatively to each other for the purpose of forming close joints between their contacting sides. In order to accomplish this end, I form a recess or chamber G in the side wall of the furnace and house there- 75 in the plate 24 through which passes the screw shaft 25 carrying the gear wheel 26. The end 27 of the shaft 25 is adapted to bear against the flat pressing plate 28, which, in turn, contacts with the face of 80 the end-block of the arch, and as the screw shaft is actuated and fed inward toward the block through the medium of the worm 29 meshing with the gear 26 the bricks may be forced one against the other to form a solid 85 wall. As will be seen by reference to Fig. 3, the shaft 30 of the worm 29 is turned by the hand wheel 31, said shaft being in the supporting yoke-plate 32 formed on the bracket 33. If desired, this means of forcing the bricks into and out of contact, at their sides, may be arranged upon both sides 90 of the furnace.

From the above description taken in connection with the accompanying drawings, 95 the construction and operation of my improvement will be readily apparent. When the bricks are to be assembled each alternate one is covered with the asbestos cloth, as heretofore described. Then the bricks are 100 successively placed in position with one shoulder resting upon the flange of the tubular air bar, while the opposite shoulder is engaged by the hooked or turned end of the supporting hanger arm, as has been described. The arm, which has its fulcrumed point at 16, may be then adjusted through the medium of the screw rod 21 to secure the brick tightly in position. When all the 105 bricks forming the wall have been assembled, the hand wheel 31 may be turned to bring their vertical faces tightly in contact, and the wall is then completed. Should one 110 of the bricks be burned or otherwise destroyed, it is only necessary to turn the adjusting nut 23 upon the screw rod 21 and loosen the grasp of the hanger arm upon the brick or block, and the latter may then be 115 easily and quickly removed from place and another substituted in its stead without disturbing or affecting the adjoining block.

It will be observed that I have provided an exceedingly simple yet advantageous construction of wall, and while I have herein shown and described a preferred embodiment of my invention, I wish it to be understood that I do not confine myself to all the precise details thereof, as there may be modification and variation in certain respects without departing from the spirit of 120 125 130

the invention or sacrificing any of the advantages thereof.

What I claim is:

1. The combination with a furnace, of a fire wall therefor comprising a plurality of bricks, means supporting the bricks adjacent one end thereof, and means operable from outside the furnace wall for completing the support of the bricks, and for securing each of the bricks in position independently of the other.

2. The combination with a furnace, of a fire wall therefor comprising a plurality of bricks, means for supporting the bricks adjacent one end thereof, adjustable means for completing the support of the bricks, and for securing said bricks in position, and means extending through a portion of the front wall of the furnace and engaging with said adjustable means, for operating the same.

3. A structure of the class described, comprising a fire wall formed of a plurality of removable bricks, means for supporting the bricks adjacent one end thereof, adjustable mechanism for completing the support of said bricks and securing said bricks in position and means extending through a portion of the wall of the furnace and engaging with said mechanism for operating the same.

4. A structure of the class described comprising a fire wall formed of bricks, a stationary support for one end of said bricks, and pivoted means operable from outside the front of the furnace for engaging with and holding said bricks.

5. The combination with a furnace, of a fire wall arranged near the mouth thereof, said wall comprising separable bricks, a stationary support for one end of the bricks, supporting lugs, and means fulcrumed to the supporting lugs and engaging with and completing the support of said bricks.

6. A fire wall, comprising a stationary bar having a longitudinally extending flange, a plurality of bricks resting thereon, and supported adjacent one end thereby, supporting devices fulcrumed above said bar and designed to engage with and retain the bricks in position, and means operable from outside the furnace for operating said supporting devices.

7. In a fire wall, the combination of a stationary support, a brick resting thereon and supported adjacent one end thereby, a hanger arm pivoted adjacent to the stationary support and adapted to engage with said brick, and complete the support of the same, and means for adjusting the hanger arm.

8. In a fire wall the combination of a plurality of removable bricks, means for supporting said bricks independently adjacent one end thereof, pivoted means operable from outside the furnace wall for completing the support of said bricks, and means adapted to bear against certain of said bricks to bring and maintain all of said bricks closely together.

9. In a fire wall the combination of a plurality of removable bricks, each brick having shouldered portions, and an inclined face, a support for the bricks adjacent one end thereof, and pivoted means engaging with the shouldered portion of each brick for completing the support of said brick independently of the others, said means being operable upon its pivot to effect the removal of said brick.

10. In a fire wall, a tubular bar having a flange at one side thereof, a brick adapted to have an edge resting on said flange, an angular arm pivoted above the flange and designed to engage with an opposite edge of the brick, and operable upon its pivot to be brought out of engagement with said edge.

11. The combination with a furnace having a recess adjacent to the mouth thereof, of a fire wall comprising a plurality of removable bricks and arranged to cut off communication between the mouth and the recess, a bar secured at the front of the recess, and adapted to support the wall adjacent one end thereof, a plurality of hanger arms pivoted to the bar and acting as devices for completing the support of the wall, and means for adjusting each of said hanger arms to permit of the removal of a brick without changing the pivotal position of said hanger arm.

12. The combination of a plurality of independently supported, removable bricks arranged to form a straight fire wall, means for supporting the bricks adjacent one end thereof, a fire-proof material between adjacent sides of adjoining bricks, means for independently securing in position each brick, means operated from outside the furnace for actuating the last-mentioned means, and means bearing against the end bricks of the wall to hold all of the bricks in juxtaposition.

In testimony whereof I have signed my name to this specification in the presence of two subscribing witnesses.
